UNITED STATES PATENT OFFICE.

WALTER DAVID NIEDERER, OF PRESCOTT, ARIZONA.

DESIGN FOR A NECKTIE.

54,953.

Specification for Design.

Patented Apr. 20, 1920.

Application filed December 6, 1918. Serial No. 265,647. Term of patent 14 years.

To all whom it may concern:

Be it known that I, WALTER DAVID NIEDERER, a citizen of Switzerland, residing at Prescott, in the county of Gila and State of Arizona, have invented a new, original, and ornamental Design for Neckties, of which the following is a specification, reference being had to the accompanying drawing, forming a part thereof.

The figure is a view of a necktie, showing my new design.

I claim:—

The ornamental design for a necktie, as shown.

WALTER DAVID NIEDERER.
